DESIGN FOR A COVER PLATE FOR A TYPEWRITING MACHINE

Russell E. Benner, Buffalo, N. Y., assignor to Remington Rand Inc., New York, N. Y., a corporation of Delaware

Application January 17, 1934, Serial No. 50,433

Term of patent 7 years

To all whom it may concern:

Be it known that I, RUSSELL E. BENNER, a citizen of the United States, residing at Buffalo, in the county of Erie and State of New York, have invented a new, original, and ornamental Design for a Cover Plate for Typewriting Machines, of which the following is a specification, reference being had to the accompanying drawings forming a part thereof.

Fig. 1 is a perspective view of a cover plate for typewriting machines showing my design.

Fig. 2 is a top plan view of the same.

Fig. 3 is an end view of the same.

I claim:

The ornamental design for a cover plate for a typewriting machine as shown.

Signed at Buffalo, in the county of Erie and State of New York this 15th day of January, 1934.

RUSSELL E. BENNER.
